Primary Examiner — Michael A Pratt*(74) Attorney, Agent, or Firm* — The Webb Law Firm(57) **CLAIM**

The ornamental design for a lead-free rimfire projectile, as shown and described.

DESCRIPTION

FIG. 1 is a front view of a lead-free rimfire projectile in accordance with an embodiment of the present invention, with the rear view, right side view, and left side view of the rimfire projectile being a mirror image thereof;

FIG. 2 is a cross-sectional view taken along the line 2-2 of the rimfire projectile shown in FIG. 1;

FIG. 3 is a top view of the rimfire projectile shown in FIG. 1;

FIG. 4 is a bottom view of the rimfire projectile shown in FIG. 1;

FIG. 5 is a bottomwardly directed perspective view of the rimfire projectile shown in FIG. 1; and,

FIG. 6 is a topwardly directed perspective view of the rimfire projectile shown in FIG. 1.
